SASH HOLDER

Chester O. Goserud, St. Paul, Minn.

Application August 24, 1933, Serial No. 686,546

4 Claims. (Cl. 292—275)

My invention relates to sash holders and has for its object to provide a sash holder by means of which a swinging sash such as casement, cellar and storm sash may be held in adjusted position.

5 An object of the invention resides in providing a sash holder by means of which the sash is securely held in position and by means of which the sash may be readily adjusted.

Another object of the invention resides in providing a sash holder which will retain its adjustment for an extended period of time and which when desired may be readily readjusted.

A still further object of the invention resides in providing the sash holder with two arms pivoted together, one of said arms consisting of two leaves straddling the other arm, and in further providing friction washers disposed between said arms and a pintle passing through said washers and arms for pivoting the same with respect to 20 one another.

An object of the invention resides in placing washers on opposite sides of one of said arms and in providing means for restraining rotational movement of said washers with respect to the other arm to provide friction against both of the 25 surfaces of the first named arm.

Another object of the invention resides in constructing one of the arms with a head and in further constructing said arm with a strap having 30 another head thereon adapted to be bent to overlie the first named head and in disposing such structure between the leaves of the other arm.

An object of the invention resides in providing friction washers between all of the parts of said 35 arms and in further employing a bolt extending through said washers and the parts of said arms for drawing the same together to procure friction therebetween.

A still further object of the invention resides 40 in providing a bolt with a polysided shank and in constructing said washers with polysided openings adapted to fit over said shank whereby the said washers are restrained from rotational movement.

45 Another object of the invention resides in constructing a part of one of said arms through which the bolt extends with a polysided opening adapted to hold the bolt from rotation with respect to said arm.

50 A feature of the invention resides in providing the other of said arms with a circular opening through which said bolt extends, said arm being journaled through said opening upon the corners of the shank of the bolt.

55 Another object of the invention resides in con-

structing one of said arms with a stop adapted to cooperate with the base of the mounting to which said arm is pivoted by means of which the movement of said arm may be limited with respect to the sash to which the mounting is attached. 5

A still further object of the invention resides in constructing the bracket to which one of the jointed arms is pivoted with a base portion adapted to extend along the upright frame member of the window frame and with a flange projecting outwardly from said base portion and adapted to be attached to the horizontal frame member of the window frame and to further construct said bracket with an offset portion terminating in an ear projecting outwardly therefrom and in which one of the arms of the holder is pivoted. 15

Other objects of the invention reside in the novel combination and arrangement of parts and in the details of construction hereinafter illustrated and/or described. 20

In the drawing:

Fig. 1 is an inverted plan sectional view of a portion of a casement window illustrating the application of an embodiment of my invention 25 thereto.

Fig. 2 is a view similar to Fig. 1 showing the sash in open position.

Fig. 3 is a sectional elevational view taken on line 3—3 of Fig. 1. 30

Fig. 4 is a sectional detail view taken on line 4—4 of Fig. 2 and drawn to a larger scale.

In the use of casement, cellar and storm sash and similar swinging sash, considerable annoyance and inconvenience is encountered in causing 35 the sash to remain open at any predetermined position. The present invention provides a construction by means of which the sash may be readily swung into any desired open position and when so disposed will be firmly held in such position. 40

For the purpose of illustrating the application of my invention I have shown in the drawing a part of a casement window which is indicated in its entirety by the reference numeral 10. This 45 casement window comprises a frame 11 consisting of upright frame members 12 and a header 13 together with such other parts as are usually employed in the construction of window frames. Such construction forming no particular feature 50 of the invention has not been illustrated in this application. The window 10 further includes a swinging sash 15 which is hinged to the frame 12 through hinges 16. The sash 15 fits into a rabbet 55

17 in the frame 12 by means of which a water tight connection is afforded.

My improved invention proper as best shown in Fig. 1 consists of two arms 18 and 19. The 5 two arms 18 and 19 are pivoted together through a joint 20 illustrated in detail in Fig. 3 while the arm 19 is pivoted to a mounting 21 adapted to be secured to the sash 15 and the arm 18 is pivoted to a bracket 22 adapted to be secured to the frame 10 12 of the window. These parts will now be described in detail.

The arm 18 is preferably constructed of sheet metal and consists of an elongated portion 122 terminating at one end in a head 23 circular in 15 form and at its other end in a similarly constructed head 24. At the first named end of the arm 18 is provided a strap 25 which is integral with said arm and which is bent outwardly therefrom to form an ear 26 overlying the end of the 20 elongated portion 122 of said arm. This ear is constructed with a head 27 corresponding with the head 23 and spaced therefrom. Head 27 is also circular in form and the two heads are coaxially disposed. The elongated portion 122 of 25 arm 18 is offset as indicated at 28 to cause the major portion of said arm to extend medially with respect to the two heads 23 and 27.

The arm 19 consists of two leaves 29 and 30 which are identical in construction. The leaf 29 30 comprises an elongated portion 31 terminating at one end in a head 32 of the same size and shape as the heads 23 and 27 and at the other end in a head 33 similar to the head 32 but slightly smaller in dimension.

35 The joint 20 by means of which the two arms 18 and 19 are pivoted together is constructed as follows: The two heads 23 and 27 are disposed between the heads 32 of leaves 29 and 30 and washers 34 and 35 lie between the respective 40 pairs of heads. These washers are preferably constructed of fibre or some other suitable friction material by means of which friction may be provided between the heads of the two arms so that the arms are retained in any adjusted position. Between the two heads 23 and 27 is disposed a metal washer 63 and on each side thereof fiber washers 61 and 62 which engage the inner surfaces of the heads 23 and 27 of arm 18. A bolt 64 extends through all of the said heads and the 45 washers therebetween. Bolt 64 is constructed with a head 164 seated against the head 32 of leaf 30 and is further provided with a nut 168 which is adapted to screw up against the head 32 of leaf 29 and to urge the parts together. 50 Bolt 64 is constructed with a square portion 65 adapted to pass through the head 32 of leaf 30 and through the washers 35, 62, 63 and 61. The shank of bolt 64 is further constructed with a cylindrical portion 66 which is threaded as indicated at 67 to receive the nut 168. The two 55 heads 23 and 27 of arm 18 rotate with respect to the bolt 64, head 23 being constructed with a round hole journaled on the cylindrical portion 66 of the shank of bolt 64 while the head 27 is journaled on the corners of the square portion 65 of the shank of said bolt. Washer 63 fits on the square portion 65 of bolt 64 and is held from rotation thereby. Washers 61 and 62 are similarly held from rotation by the square portion 60 65 of bolt 64. By means of this construction added friction members are disposed on the joint which give a greater degree of friction to the joint and which permit of firmly and rigidly holding the sash in open position. In addition the metal washer 63 between the friction washers 61

and 62 helps to hold said washers from rotation and prevents the hole through said washers from becoming reamed out.

The arm 18 is pivotally connected to the sash 15 through the mounting 21 which will now be 5 described in detail. Mounting 21 is constructed of sheet metal and is provided with a base 40 having an ear 41 extending upwardly therefrom. The ear 41 is of a width less than that of the base and is struck out of the metal of said mounting to leave portions 42 and 43 on either side of 10 said ear which form abutments for engagement with the arm 18 as will be presently described. The head 24 formed on arm 18 is pivoted to the ear 41 through a stud 68. This stud is formed 15 with a shank 69 extending through the head 24 of arm 18, which shank is riveted upon the head 24 as indicated at 70. The stud 68 is adapted to extend through an opening 71 in the ear 41 of mounting 21 by means of which the said arm 18 20 is journaled to the mounting. Stud 68 is arranged upon the under side of arm 18 so that the said arm is held by gravity against the ear 41 and the said stud prevented from being disengaged from the mounting. By means of this 25 construction the sash holder may be readily detached from the window when it becomes necessary to remove the sash therefrom. Base 40 is constructed with holes not shown through which screws 58 may extend for attaching the mount- 30 ing to the window proper.

The bracket 22 is constructed similar to the mounting 21 and is formed from sheet metal, being provided with a base 48 and a flange 49 extending outwardly therefrom. This flange is 35 constructed with an ear 50 projecting outwardly therefrom and in a plane parallel to and spaced from the plane of the base 48. The two leaves 29 and 30 of arm 19 are pivoted to the ear 50. Between the said ear 50 and the heads 33 are 40 disposed friction washers 51 and 52. A bolt 53 passes jointly through the two heads 33, the washers 51 and 52 and the ear 50. This bolt is constructed with a square shank 54 which is received within square holes in the two heads 33 45 and the washers 51 and 52. The ear 50, however, is constructed with a circular hole forming a bearing on the corners of the shank 54 of said bolt. By means of this construction the washers 51 and 52 are caused to rotate with the leaves 50 29 and 30, thereby providing friction on both sides of the ear 50 of bracket 22. The base 47 and flange 48 of bracket 22 are drilled to receive screws 59 by means of which the said bracket may be attached to the window proper. 55

For the purpose of limiting the movement of the arm 18 with respect to mounting 21, the arm 18 is constructed with two projections 55 and 56, which form stops adapted to engage the abutments 42 and 43 on the base 40 of said mounting. 60 These stops are so situated that when the sash is in closed position, the two arms are held in fully closed position and in such a manner that the same clear the sash. These stops are further arranged so that when the arms are in extended position and the window fully opened, said arms clear the window as shown in Fig. 2. By means of this construction injury to the window is prevented, and the sash holder caused to operate between fixed limits. 65

The manner of installing my invention is as follows: The arms 18 and 19 are brought together and the mounting 21 swung about its pivot until the abutment 43 engages the stop 55 on arm 18. The arms then occupy the position 70 75

shown in Fig. 1. With the parts so arranged mounting 21 is attached to the upper rail of the sash 15 by means of screws 58. In a similar manner bracket 22 is secured to the frame 11 by means of screws 59. Nut 168 is then tightened to give the desired amount of friction in the joint 20 and the holder is then ready for use.

In the use of the invention it is merely necessary to swing the sash inwardly and outwardly through the pull or other device provided on the sash for that purpose. As the sash swings upon its hinges 16, the joint 20 provides suitable friction to hold the sash in adjusted position. When the sash is fully open, stop 56 engages abutment 42 and serves to prevent further movement of the sash.

My invention is highly advantageous in that an extremely simple and practical device is provided by means of which swinging sash and particularly casement sash may be held in any adjusted position. By means of the particular joints utilized suitable friction can be provided and at the same time the degree of friction adjusted to meet the requirements. By means of my improved construction, the joints will last indefinitely and when wear occurs the same may be readily taken up by tightening the various nuts of the bolts forming the pintles of the joints. By the use of bolts with square shanks the friction washers and parts of one of the arms can be held from rotation, thereby procuring friction on both sides of the heads of the other arm. In this manner greater friction can be procured than would otherwise be possible. By holding the friction washers from rotation with respect to the bolt, said washers are prevented from cutting out and greater life hence results. By means of the stops on the arm attached to the sash and by means of the abutments formed on the mounting to which said arm is secured, the movement of such arm is limited to prevent the same from engaging the sash proper. This prevents injury to the sash. By means of the particular construction of the bracket of my invention, the holder can also be mounted at the bottom of the sash and on a sloping window sill. With my invention, friction is provided at two joints instead of one, thereby preventing rattling of the holder and sash when the device is in use.

Changes in the specific form of my invention, as herein disclosed, may be made within the scope of what is claimed without departing from the spirit of my invention.

Having described my invention, what I claim

as new and desire to protect by Letters Patent is:

1. In a sash holder, two arms, a pintle held from rotation relative to one of said arms, a metallic washer on said pintle, means on said pintle for holding said metallic washer from rotation relative to said pintle, friction washers between said arms and metallic washer, means for holding said friction washers from rotation relative to said pintle, and means for drawing said arms and washers together to procure friction therebetween.

2. In a sash holder, two arms, a pintle, a non-circular portion on said pintle engaging one of said arms for holding said pintle from rotation relative to said arm, a metallic washer on said pintle, said washer having a part engaging said non-circular portion and being held from rotation relative to said pintle thereby, friction washers between said arms and metallic washer and engaging said non-circular portion and being held from rotation thereby, and means for drawing said arms and washers together to procure friction therebetween.

3. In a sash holder, an arm, a second arm having two parts overlying one another and disposed adjacent said first named arm, a pintle extending through said arms and held from rotation relative to said first named arm, a metal washer on said pintle between the parts of said second named arm and held from rotation relative to said pintle, and two friction washers on said pintle between said metal washer and the parts of the second named arm, said friction washers being held from rotation relative to said pintle, and means for drawing said parts together to procure friction therebetween.

4. In a sash holder, an arm, a second arm having two parts overlying one another and disposed adjacent said first named arm, a pintle extending through said arms, a non-circular portion on said pintle for holding said first named arm from rotation relative to said pintle, a metallic washer on said pintle between the parts of said second named arm, said washer having a part engaging said non-circular portion and being held from rotation relative to said pintle thereby, two friction washers on said pintle between said metallic washers and the parts of said second named arm, said friction washers having parts engaging the non-circular portion of said pintle and being held from rotation relative to said pintle, and means for drawing said parts together to procure friction therebetween.

CHESTER O. GOSERUD.
